UNITED STATES PATENT OFFICE.

FRANCIS D. ALGOOD, OF LEESVILLE, LOUISIANA.

BRACE.

1,162,542.

Specification of Letters Patent.

Patented Nov. 30, 1915.

Application filed November 13, 1913. Serial No. 800,881.

To all whom it may concern:

Be it known that I, FRANCIS D. ALGOOD, a citizen of the United States, residing at Leesville, in the parish of Vernon and State of Louisiana, have invented certain new and useful Improvements in Braces; and I do hereby declare the following to be a full, clear, and exact description of the invention, such as will enable others skilled in the art 10 to which it appertains to make and use the same.

This invention relates to a wagon construction and more particularly to the construction of the shafts thereof and the principal object of my invention is to provide a shaft construction whereby there is no mortise and tenon connection between the shaft and the cross piece, suitable parts being provided forming a strong connection therebetween.

Another object of the invention is to provide a brace adapted to be secured to the cross piece and shaft of a wagon for forming a strong connection therebetween.

With these and other objects in view the invention resides in the construction, combination, and arrangement of parts, herein-after more fully described and claimed and illustrated in the accompanying drawing in which like characters of reference indicate like parts throughout the several figures, of which,

Figure 1, represents a perspective view of a pair of wagon shafts constructed according to my invention. Fig. 2, represents a horizontal, sectional view through one end of one of the shafts and the adjacent portion of the cross piece, strengthening bars being shown on the braces. Fig. 3, represents a top plan view of one end of one of the shafts and the adjacent portion of the cross piece showing the use of a modified form of the brace. Fig. 4, represents a perspective view of one of the shafts, the cross piece and brace being removed. Fig. 5, represents a perspective view of one end of the cross piece having the brace secured thereto, said cross piece being removed from the shafts, and Fig. 6 represents a perspective view of a modified form of brace.

Referring more particularly to the drawing, shafts 5 are connected near their ends by a cross piece 6, which is squared off at its ends and which is not connected to the shafts by mortise and tenon joint as is the usual construction. Braces 7 which are in the

form of strips of metal bent at their middle portion to form right angle arms are secured at each end of cross piece 6 on opposite sides thereof by means of bolts 8, which pass through openings in the arms of the braces and which also pass through openings in the cross piece 6, a pair of bolts connecting the arms of the braces lying against the cross piece at opposite ends of said arms, said bolts 65 passing through both arms and through the cross piece. Shafts 5 are provided with openings 9 adapted to register with openings 10 in the oppositely extending arms of braces 7, and bolts 11 are passed through said oppositely extending arms and through the openings in the shafts for securing the braces to the shafts and thereby providing a strong connection between the cross piece and the shafts and one which is free from the mortise and tenon joint ordinarily used.

As shown in Fig. 2, the braces are strengthened by the addition of a bar 18, connecting the arms of each brace 7, at their outer ends, and secured in place by means of the same 80 bolts which connect the outer ends of the arm to the cross piece and shafts respectively, said bolts passing through the ends of the rods, said ends being bent to lie flat against the brace arms.

The brace illustrated in Figs. 3 and 6 comprises a strip of metal bent at right angles, and from the arms 12 thereof are stamped tongues 13, said tongues being inwardly bent from the outer ends of the arms 90 and toward each other, one of said tongues being provided with a groove 14 in which a flange or rib 15, formed on the end of the opposite tongue is adapted to be engaged. The arms 12 are provided at their opposite 95 ends with openings 16 through which bolts are adapted to pass for securing the cross piece to the shaft similar to the manner previously described. Should the shafts become warped or bent from their original position relative to the cross piece when the brace illustrated in Figs. 3 and 6 is used, it is evident that the tongues 13 will become somewhat warped relative to each other and that a blow at the meeting edges of the 100 tongues 13 will force them into their original position and will thus restore the shafts to their original position relative to the cross piece. However, it is evident that because of the tongues 13 forming a brace for the 110 brace proper, that a very strong construction is provided and that an exceedingly strong

exertion on the shaft will be necessary for warping the same relatively to the cross piece.

Although I have described the preferred embodiment of my invention I may desire to make such changes in the construction, combination, and arrangement of parts as do not depart from the spirit of the invention and the scope of the appended claim.

Having thus fully described my invention what I claim as new and desire to secure by Letters Patent is:—

A brace for vehicle shafts, consisting of a single bar of metal comprising a pair of angularly disposed arms, and integral reinforcing tongues struck out from the body portions of said arms and projecting inwardly from near the ends of said arms, said tongues disposed in longitudinal alignment with their ends abutting each other,

the abutting end of one of said tongues having a groove extending transversely of the line of strain and intersecting the axial center of the longitudinal trend, the abutting end of the other of said tongues having a correspondingly disposed rib co-operatively seated within said groove, said rib and said groove retaining said tongues in abutting and aligned relation for resisting compress strains exerted upon said tongues by the force upon the ends of said arms, but permitting slight vertical movement of said tongues relative to each other.

In testimony whereof I have signed my name to this specification in the presence of two subscribing witnesses.

FRANCIS D. ALLGOOD.
